UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A TALCUM-BOX.

46,865.

Specification for Design.

Patented Jan. 19, 1915.

Application filed March 23, 1914. Serial No. 826,825. Term of patent 7 years.

To all whom it may concern:

Be it known that I, EDMUND HOFFMAN, a citizen of the United States, residing at 320 Eighth avenue, Brooklyn, in the county of Kings and State of New York, have invented a new, original, and ornamental Design for a Talcum-Box, of which the following is a specification, reference being had to the accompanying drawing, forming part thereof.

In the drawing, Figure 1 is a front elevation, Fig 2 is a side elevation and Fig. 3 a bottom view of a talcum box showing my new design.

The design is characterized by a body which is rectangular in cross-section, of

greater length than width, rounded at the corners and tapered at a small angle from near the bottom toward the top. Such body is formed with a rectangular flat bottom of less area than the horizontal sectional area of the body, and from the boundary of said bottom the box is rounded outward and upward so that its configuration flows into the configuration of the body.

I claim:

The ornamental design for a talcum box, as shown and described.

EDMUND HOFFMAN.
